US0D1059993S

(12) **United States Design Patent** (10) **Patent No.:** **US D1,059,993 S**
(45) **Date of Patent:** **** Feb. 4, 2025**

(54) **KNOB**

- (71) Applicant: **Dongguan Xinwangda Outdoor Products Co., Ltd.**, Guangdong (CN)
- (72) Inventor: **Mengru Mo**, Guangxi (CN)
- (73) Assignee: **Dongguan Xinwangda Outdoor Products Co., Ltd.**, Dongguan (CN)

(**) Term: **15 Years**

(21) Appl. No.: **29/970,929**

(22) Filed: **Oct. 31, 2024**

(30) **Foreign Application Priority Data**

- Sep. 13, 2024 (CN) 202430586643.3
- (51) **LOC (15) Cl.** **02-07**

(57) **CLAIM**

The ornamental design for a knob, as shown and described.

DESCRIPTION

FIG. 1 is a perspective view of a knob showing my new design;

FIG. 2 is another perspective view thereof;

FIG. 3 is a front elevation view thereof;

FIG. 4 is a back elevation view thereof;

FIG. 5 is a left side elevation view thereof;

FIG. 6 is a right side elevation view thereof;

FIG. 7 is a top plan view thereof;

FIG. 8 is a bottom plan view thereof; and,

FIG. 9 is a perspective view of the knob of FIG. 1 as it would be positioned during use.

The broken lines depict portions of the knob that form no part of the claimed design.

1 Claim, 9 Drawing Sheets
